Inventor:
Samuel F. Nahm

By C. A. Mason, Atty.

UNITED STATES PATENT OFFICE.

SUNSHINE F. NAHM, OF BOWLING GREEN, KENTUCKY.

CLOSURE FOR CONTAINERS.

Application filed January 8, 1923. Serial No. 611,377.

To all whom it may concern:

Be it known that I, SUNSHINE F. NAHM, citizen of the United States of America, residing at Bowling Green, in the county 5 of Warren and State of Kentucky, have invented certain new and useful Improvements in Closures for Containers, of which the following is a full, clear, and exact description.

10 This invention relates to closures, and particularly to a measuring device which is formed as a part of the closure.

15 The invention provides a top or closure for containers of box-like form, or cartons which is provided, as a matter of convenience, with a cavity or depression depressed therein so as to lie below the upper surface of said top, and which will be of the correct size to measure accurately a pre- 20 determined quantity of material, such as of the substance which is in the container. By providing the spoon or other measuring element as a part of the top to the vessel, it will be seen that the measuring operation 25 may be performed at any time, and without the necessity of procuring a spoon, or other measuring element which, under some conditions, would be quite inconvenient.

30 In the accompanying drawings, which illustrate by way of example, a device embodying the invention,

Fig. 1 shows the top of a container, in plan, together with the measuring device, and

35 Fig. 2 is a sectional view on the line 2—2, Fig. 1.

A suitable container 5, for any substance in solid, liquid, or powdered form, is provided with a slip-cover 3, having a depending 40 portion 4 which snugly embraces the top of the vessel 5. The cover 3 is herein shown as provided with a depression 6, formed integral with the cover and made in the form of a spoon. The depression 6 may be of the 45 size of a teaspoon, a dessert spoon, or a table spoon, and is for the purpose of measuring portions of the contents of the container 5 as the same are intended for use. If desired, in lieu of having the depression 50 6 in the form of a spoon, it may be circular, or of any other desired configuration, provided, of course, it is of the size to accurately measure a predetermined quan-

tity of material, as for example, the material in the container 5.

Although I have illustrated the measuring cavity 6 as being a depression of the material of the top 3, it is obvious that the bowl of a spoon may be set in a cut out portion of the top, thereby constituting a 60 continuation of the top to the same extent as where the material is depressed as in the form illustrated in the drawings.

It will be obvious that with a measuring cavity depressed in the top of a container 65 it will be unnecessary to find a spoon to measure a quantity of the material as the measuring implement is formed as a part of the top of the container, and is always at hand. With the spoon positioned as shown 70 in the drawings, with its point or front end adjacent to a corner of the container top, the material which is measured in the spoon-shaped depression may be readily poured 75 into a glass or other vessel by resting the lower edge of the corner of the flange 4 upon the top of said vessel, and tilting the closure 3 to discharge the contents of the spoon 6.

Having thus described my invention, 80 what I claim as new and desire to secure by Letters Patent is:

1. A top for a container made of sheet material, and provided with a cavity which occupies a fractional part of its entire upper surface and which lies below that portion of said surface which is not occupied by the cavity, said cavity being of a size to measure a predetermined quantity of material.

2. A top for a container of sheet material having a spoon-shaped depression which lies wholly below the upper surface of the top and occupies a fractional part of said top only, said depression being formed out 95 of the material of the top by forcing said material out of the plane of the upper surface of said top.

3. A rectangular-shaped top for a container made of sheet material, the upper portion of said top being depressed to present a spoon-shaped cavity, said cavity located with its major axis coincident with the diagonal connecting two corners of said top, the forward end of said cavity being 105 arranged adjacent to a corner of the top.

4. A rectangular-shaped top for containers made of sheet material and provided with a depression or cavity in the shape of a spoon for measuring material, the point or forward end of the spoon-shaped depression being located adjacent one corner of the top.

In testimony whereof I have hereunto set my hand this 30th day of December A. D. 1922.

SUNSHINE F. NAHM.
